EDWARD T. CURRAN.

By Raymond A. Parker

Attorney

UNITED STATES PATENT OFFICE.

EDWARD T. CURRAN, OF DETROIT, MICHIGAN.

RADIATOR.

1,389,631.

Specification of Letters Patent. Patented Sept. 6, 1921.

Application filed December 23, 1918. Serial No. 267,900.

To all whom it may concern:

Be it known that I, EDWARD T. CURRAN, a citizen of the United States, residing at Detroit, county of Wayne, State of Michigan, have invented a certain new and useful Improvement in Radiators, and declare the following to be a full, clear, and exact description of the same, such as will enable others skilled in the art to which it pertains to make and use the same, reference being had to the accompanying drawings, which form a part of this specification.

My invention relates to radiators for airplanes and automobiles and devices of like character and it consists in the construction and combination hereinafter specified. It pertains particularly to that type of radiator which is made of flattened steel tubes opening into headers above and below the same with which said tubes communicate and which tubes are welded at their meeting edges and also to the headers respectively.

In the drawings:

Figure 1 represents the rear elevation of such a radiator.

Fig. 2 is a sectional view on the line Y—Y Fig. 1.

Fig. 3 is a section on the line X—X of Fig. 2.

Fig. 4 is a perspective view of a few of the tubes and the arrangement and manner of supporting the same.

Similar letters refer to similar parts.

In the drawings A represents the upper header, or tank, into which the tubes open; B represents the lower tank into which the lower end of the tubes also opens. CC represents the tubes. These tubes are formed by bending sheet metal back upon itself forming a space between them; the two edges that are brought together are welded at C', see Fig. 3, forming a flattened tube. At the lower rear corners of said tubes at C² they are welded together and welded to the header B. The lower front corners C³ (Fig. 2) are also welded to the header B, see Fig. 4. The upper front and rear corners C⁵ and C⁶ are welded to the header A. To

form the tube space and prevent the tubes from collapsing knobs are welded on the inner face of the metal, as shown at C⁴ in Fig. 3 so that when the metal is folded back upon itself to be welded at C' the

knob approaches or touches the opposite 55 wall of the tube and spaces the walls apart as shown at C⁴. These knobs are also shown in Fig. 2 at C⁴ C⁴ which is a sectional drawing through the center of one of the tubes on the line Y—Y of Fig. 1. These welded on 60 knobs prevent the tubes from collapsing. Across the rear edges or where the tubes are welded to fashion them, a line of autogenous welding is shown at D which spaces the tubes and prevents their coming 65 in contact with each other and closing off the air passages therethrough, also acting as a stay by fixing rigidly their relative positions.

At E, Fig. 2, is the inlet pipe and F is 70 the outlet pipe for the cooling water to the engine. The inlet pipe has a shield or is turned downwardly at E' so as to more effectively direct the entering current of water downward into the cooling tubes C C. 75 G is the filling cap which is of the usual construction.

What I claim is:

1. An autogenous welded radiator comprising an assemblage of flattened steel 80 tubes, and knobs formed of separate material from that of the tubes welded on the interior flat surfaces of said tubes and bridging the space between opposite faces of the tubes to prevent collapsing, substantially as described.

2. An autogenous welded radiator, comprising a series of flattened steel tubes formed by folding sheet steel upon itself and welded at its meeting edges, an upper 90 and a lower header, each welded to the series of tubes, a strip extending transversely of the tubes and welded to the edges of the tubes, thereby forming an autogenous cross welding whereby said tubes are 95 braced and their proper spacing maintained, and the whole formed into one autogenous welded structure, substantially as described.

3. A radiator comprising flat, substantially parallel sheet metal tubes, narrow 100 strips or rods extending transversely of the tubes and welded to their front and rear edges, whereby the spacing of the tubes is maintained, and the tubes and strips rigidly united to form an integral structure. 105

In testimony whereof, I sign this specification.

EDWARD T. CURRAN.
